Fig. 6

FIG. 1 is an elevational front view of a bottle embodying my new design;

FIG. 2 is a side view thereof;

FIG. 3 is a rear view thereof;

FIG. 4 is a bottom plan view thereof;

FIG. 5 is a fragmentary sectional view taken in the direction of the arrows on the section plane passed through section line 5—5 of FIG. 1;

FIG. 6 is a fragmentary sectional view taken in the direction of the arrows on the section plane passed through section line 6—6 of FIG. 2;

FIG. 7 is a fragmentary sectional view taken in the direction of the arrows on the section plane passed through the section line 7—7 of FIG. 3.

The dominant features of my design reside in the portions shown in full lines.

I claim:

The ornamental design for a bottle or similar article, as shown and described.
